DISTILLING, RECTIFYING, FRACTIONATING,
ING, OR WASHING COLUMN

Carl Justus Heckmann, Breslau, Germany, assignor to Maschinenfabrik Heckmann G. m. b. H.

Application August 17, 1937, Serial No. 159,528
In Germany April 23, 1937

9 Claims. (CL 261—114)

The invention relates to a distilling, rectifying, fractionating or washing column wherein the reflux takes place from bottom to bottom and the bottoms of both halves of the column are relatively displaced by half the total bottom spacing and resides therein that the distilling and so forth tunnels themselves serve directly for guiding the reflux from one bottom to the next succeeding one.

By the displacement of the bottoms of both halves of the column relatively to one another there is effected in the known manner an economy in height and by the fact that the rectifying tunnels are themselves directly passages for the reflux, all separate return pipes are unnecessary and the reflux is effected in a favourable manner in a wide stream from one bottom to another and in this way is traversed over a wide surface by the rising vapours. For the rest rectifying columns of this construction are inexpensive and efficient especially as the bottoms themselves are all constructed similarly and are therefore capable of being erected and exchanged easily. Also inconvenient packings between the separate bottoms are omitted and the column always has a sufficient reflux reserve.

In the accompanying drawings there is shown a form of construction of the column and of the bottoms serving for the erection of the column.

Fig. 1 is a partial longitudinal section of the columns along the line I—I of Fig. 2.

Fig. 2 is a plan of one of the column bottoms.

Fig. 3 is an end view of Fig. 2 looking from the left.

Fig. 4 is an end view of Fig. 2 looking from the right.

Fig. 5 is a perspective view of a number of bottoms, parts of one bottom being broken away.

The column consists of the usual, preferably cylindrical casing 1, in which the steam pipe 2 enters at the bottom and from the bottom of which there extends the pipe 3 for the reflux. The vapour rising in the column passes through the pipe 4 into a condenser 5 and from here passes through the pipe 6 partly back into the column and partly through the pipe 7 as finished product to the cooler. The reflux returning into the column through the pipe 6 flows downwardly in the usual manner from bottom to bottom into the lower part of the column.

The column, according to the invention, is

filled with bottoms which are all completely alike and which bear tightly upon one another and fit, as regards their outside shape, the shape of the column. Each of these bottoms, in so far as the column is of circular cross-section, consists of a semi-circular flat and horizontally located part 8, which may be provided with a packing and strengthening rim. At the rim of the bottom 8 opening towards the middle of the column there is provided a catch or collecting gutter 9 and to this gutter are connected the rectifying or the like tunnels 10, 11, 12, 13, 14 (Fig. 3), of which a larger or smaller number may be provided as desired. The surfaces of these tunnels, as shown in Figs. 3 to 5, are in turn shaped in the form of a gutter so that the covers of the separate tunnels form reflux gutters 10a, 11a, 12a, 13a, 14a.

These gutters 10a to 14a are directly connected to the collecting gutter 9 so that the liquid which collects in the gutter 9 is distributed by this into the gutters 10a to 14a. As the surfaces of the tunnels, as shown in Fig. 1, are inclined, the liquid descending in the direction of the arrow A on to these gutters flows downwardly in the direction of the arrow B and reaches the semi-circular and flat part of the bottom 8a next below. On this bottom the liquid rises between the tunnels 10 to 14 and, by reason of the presence of the openings 15, also in the interior of these tunnels until the liquid reaches the upper edge of a weir wall 16 extending over the entire diameter of the column. Outside the tunnel 12 the liquid then passes over the partition, also extending between the separate tunnels, and passes into the collecting gutter 9a of the bottom 8a and runs over the gutter shaped tunnel tops downwardly in the direction of the arrow C, reaches the bottom 8b, runs between the separate tunnels 40 over the weir wall 16a, passes into the gutter 9b of the bottom 8b and so on. The broken arrow D above the bottom 8a indicates that the overflow takes place behind the plane of the drawing, whilst the full line arrow E above the bottom 8b indicates that the overflow takes place in the plane of the drawings.

The rising vapour passes in the direction of the arrow F through the intermediate space between the upper edge of the weir wall 16a and the lower edge of the gutter 9c behind the plane of the drawing of Fig. 1, into the tunnels of the bottom 8c, and fills the tunnels to such an extent that the reflux liquid, which tends to pass through the openings 15 into the interior of the tunnels

cannot rise above the level of the upper edge of these openings. Through the points 15c the vapour passes out on both sides of the tunnels 10 to 14 and passes in the direction of the arrows 5 G and H into the interior of the tunnels of the bottom 8b, from here passes through the openings 15b into the intermediate spaces between the tunnels and then passes in the same manner into the tunnels of the bottom 8a and from here into the tunnels of the bottom 8, whereupon it escapes 10 from these tunnels 15 and passes into the pipe 4.

Into the gutter 9 there project between the adjacent wall surfaces of the tunnels sheet metal members 17 which between the intermediate 15 spaces between the tunnels of one bottom and the gutter of the next succeeding bottom form a liquid seal.

The height of the weir plate H (Fig. 1) corresponds with the level of the reflux and this 20 must be greater than the height of liquid h above the upper edge of the openings 15 in the tunnel walls. In so far as the outflow plane from the collecting gutter of the next lower bottom does not lie above or substantially above the level of 25 the tunnels of the next higher bottom, this condition is obtained solely in that the weir wall 16 is made higher than the upper edge of the vapour passage openings in the tunnel walls.

The advantages of a column according to the 30 invention are extremely numerous. The inserted members consist of separate elements which are all entirely similar and are capable of being constructed easily from any suitable material, especially from pressed materials such as artificial resin, glass or the like. A carrying over of liquid 35 particles from one bottom to the next may be almost completely prevented as no vapour tubular members are necessary through which liquid drops are carried along in normal columns. The liquid is most efficiently distributed over each 40 bottom so that a uniform operation is possible over the whole surface of the bottom, dead points are eliminated as also separate liquid guides. The space otherwise taken up by reflux pipes is in this manner rendered useful for the actual 45 rectification. The reflux is conducted through the tunnels and here continuously heated by the vapour in the tunnels, so that also in this case there occur thermal economical advantages. The reflux flows between the tunnels on the counter- 50 current flow through the vapours whereby increased vapour and liquid mixing and favourable bottom efficiency are obtainable. Finally a large reserve can be provided for the reflux in a construction according to the invention so that the 55 column is capable of meeting a high overload as very large quantities of reflux can be conducted, without accumulations, through the column according to the invention.

Instead of the rectangular vapour outlet openings 60 15 shown in the drawings it is also possible to use otherwise shaped openings in the known manner, for example triangular notches, which if desired may also be so arranged at the lower edge of the tunnels that the lower edge of the 65 tunnels has a notched shape.

What I claim is:—

1. In a column of the character specified, the combination comprising a casing, a plurality of bottoms mounted in said casing, a plurality of 70 tunnels located over half the area of each bottom, said bottoms being mounted in spaced relation in said casing and being relatively displaced by a distance equal to half the distance between adjacent bottoms, said tunnels serving to guide the 75 material under treatment from one bottom to the

next, a plurality of gutters extending along a diameter of said casing, said gutters being associated one with each bottom and being all located in the same vertical plane, a plurality of gutters located one on each tunnel, the gutters on the 5 tunnels extending downwardly from the corresponding diametral gutters towards the periphery of said casing, a plurality of weir walls located one on each bottom, said weir walls extending parallel to said diametral gutters through said tunnels, each of said tunnels having a plurality of 10 holes in the side walls thereof, the upper edges of the weir walls being located a distance above the overflow plane of the corresponding diametral gutter which is greater than the distance between 15 the upper edge of the weir wall and the upper edge of said apertures.

2. In a column of the character specified, the combination comprising a casing, a plurality of bottoms mounted in said casing, a plurality of 20 tunnels located over half the area of each bottom, said bottoms being mounted in spaced relation in said casing and being relatively displaced by a distance equal to half the distance between adjacent bottoms, said tunnels serving to guide the material under treatment from one bottom 25 to the next, a plurality of gutters extending along a diameter of said casing, said gutters being associated one with each bottom and being all located in the same vertical plane, a plurality of 30 gutters located one on each tunnel, the gutters on the tunnels extending downwardly from the corresponding diametral gutters towards the periphery of said casing, a plurality of weir walls located one on each bottom, said weir walls extending parallel to said diametral gutters through 35 said tunnels, each of said tunnels having a plurality of holes in the side walls thereof, the upper edges of the weir walls being located a distance above the overflow plane of the corresponding diametral gutter which is greater than the distance 40 between the upper edge of the weir wall and the upper edge of said apertures, and a plurality of closure walls extending along the central plane of said diametral gutters, said closure walls dipping into the diametral gutter of the bottom next 45 below, said closure walls serving to close the spaces between adjacent tunnels.

3. A bottom for a column of the character described, comprising a circular element, a diametral gutter in said bottom dividing it into 50 two semi-circular portions, a plurality of parallel tunnels arranged parallel to one another on one circular portion, a plurality of gutters located one at the top of each tunnel, the gutters at the tops of the tunnels communicating 55 at one end with the diametral gutter and being inclined downwardly from said diametral gutter, said tunnels having apertures in the side walls thereof.

4. A bottom for a column of the character described, comprising a circular element, a diametral gutter in said bottom dividing it into two semi-circular portions, a plurality of parallel tunnels arranged parallel to one another on one circular portion, a plurality of gutters located one at the top of each tunnel, the gutters at the tops of the tunnels communicating 60 at one end with the diametral gutter and being inclined downwardly from said diametral gutter, 65 said tunnels having apertures in the side walls thereof, a weir wall extending parallel to the diametral gutter on the side of the bottom provided with the tunnels, the upper edge of said 70 weir wall being located at a higher level than 75

the upper edge of the apertures in said tunnels.

5. A bottom for a column of the character described, comprising a circular element, a diametral gutter in said bottom dividing it into two semi-circular portions, a plurality of parallel tunnels arranged parallel to one another on one circular portion, a plurality of gutters located one at the top of each tunnel, the gutters at the tops of the tunnels communicating at one end with the diametral gutter and being inclined downwardly from said diametral gutter, said tunnels having apertures in the side walls thereof, a weir wall extending parallel to the diametral gutter on the side of the bottom provided with the tunnels, the upper edge of said weir wall being located at a higher level than the upper edge of the apertures in said tunnels, and a closure wall extending parallel to said diametral gutter and closing the space between the separate tunnels, said closure wall extending downwardly beyond the lower surfaces of the tunnels.

6. A bottom for a column of the character described, comprising a circular element, a diametral gutter in said bottom dividing it into two semi-circular portions, a plurality of parallel tunnels arranged parallel to one another on one circular portion, a plurality of gutters located one at the top of each tunnel, the gutters at the tops of the tunnels communicating at one end with the diametral gutter and being inclined downwardly from said diametral gutter, said tunnels having apertures in the side walls thereof, a weir wall extending parallel to the diametral gutter on the side of the bottom provided with the tunnels, the upper edge of said weir wall being located at a higher level than the upper edge of the apertures in said tunnels, and a closure wall extending parallel to said diametral gutter and closing the space between the separate tunnels, said closure wall extending downwardly beyond the lower surfaces of the tunnels, all of said parts being formed as a complete unit from pressed or cast materials such as artificial resins, glass, extrusion castings or the like.

7. In a column of the character specified, the combination comprising a cylindrical casing, a plurality of circular bottoms mounted in said casing, a plurality of tunnels located on each of said bottoms, said tunnels extending parallel to one another from a line extending diametrically across the bottom to the periphery of the latter and covering half the area of each bottom, said bottoms being mounted in spaced relation one above the other in said casing and being relatively displaced by a distance equal to half the distance between adjacent bottoms,

whereby a portion of a bottom on which tunnels are located is under a portion free from tunnels of the bottom next above, said tunnels serving to guide the material under treatment from one bottom to the next.

8. In a column of the character specified, the combination comprising a cylindrical casing, a plurality of circular bottoms mounted in said casing, a plurality of tunnels located on each of said bottoms, said tunnels extending parallel to one another from a line extending diametrically across the bottom to the periphery of the latter and covering half the area of each bottom, said bottoms being mounted in spaced relation one above the other in said casing and being relatively displaced by a distance equal to half the distance between adjacent bottoms, whereby a portion of a bottom on which tunnels are located is under a portion free from tunnels of the bottom next above, said tunnels serving to guide the material under treatment from one bottom to the next, and a plurality of gutters, one gutter extending diametrically across each bottom, whilst the remaining gutters are located one at the top of each tunnel, said last mentioned gutters extending from the respective diametrical gutters and being inclined downwardly from the diametrical gutter towards the periphery of said bottom.

9. In a column of the character specified, the combination comprising a cylindrical casing, a plurality of circular bottoms mounted in said casing, a plurality of tunnels located on each of said bottoms, said tunnels extending parallel to one another from a line extending diametrically across the bottom to the periphery of the latter and covering half the area of each bottom, said bottoms being mounted in spaced relation one above the other in said casing and being relatively displaced by a distance equal to half the distance between adjacent bottoms, whereby a portion of a bottom on which tunnels are located is under a portion free from tunnels of the bottom next above, said tunnels serving to guide the material under treatment from one bottom to the next, each of said tunnels having a plurality of apertures in the side walls thereof, and a plurality of gutters, one gutter extending diametrically across each bottom, said diametrical gutters being all located in the same vertical plane, whilst the remaining gutters are located one at the top of each tunnel, said last mentioned gutters extending from the respective diametrical gutters and being inclined downwardly from the diametrical gutter towards the periphery of said bottom.

CARL JUSTUS HECKMANN.
